EYELET STAY TAPING MACHINE

Walter P. Osgood, Malden, Mass.

Application March 1, 1937, Serial No. 128,396

35 Claims. (Cl. 12—51)

In its broadest aspect the present invention relates to machines which are used in the manufacture of shoes to apply a reinforcing strip to a shoe upper part comprising either a sheet of pliable material or the quarters joined by a back seam. More specifically, the present invention relates to machines which are used to apply tape to that portion of the flesh face of a shoe upper part which is to be provided with a row of holes 5 each forming or receiving one element of a closure. In some shoes the holes receive buttons, in others hooks, and in others eyelets. In the shoe industry the area in which the row of holes is to be formed and which is to be taped prior 10 to the hole forming operation, is called the button row, the hook row or the eyelet row, depending upon the type of closure with which the shoe is to be provided. For convenience the phrase "eyelet row" is used herein to designate 15 the taped area irrespective of the ultimate use of the row of holes to be formed therein.

Usually the eyelet row is covered by a piece of tape placed alongside but without the plies of the folded margin of the shoe upper part. The 20 folded margin has a bent run extending along at least one end of the eyelet row. Usually both ends of the eyelet row are bent in opposite directions. It has been proposed heretofore to provide tape-applying machines with means for shaping 25 the ends of the tape to cause them to fit the bent runs at the ends of the eyelet row, but in order to do this it was considered necessary to provide the taping machines with two cutting devices operating successively which rendered the 30 machines complicated and costly to manufacture and operate.

One of the principal objects of the present invention is to provide a tape-applying machine with a single cutting device which will shape at 35 least one edge of the reinforcing stay so that it will fit the bent run on at least one end of the eyelet row.

Another object of the present invention is to produce a taping machine in which the tape-severing knife is thrown automatically out of 40 operation.

Another object of the present invention is to produce a taping machine in which the tape-applying mechanism withdraws the tape as 45 needed from a source of slack tape supply which is replenished by a pull-off device operating automatically, prior to the slack tape withdrawing action of the tape-applying mechanism, to pull 50 tape from the main source of supply and thus

free the pulled off tape from the main source of supply tension.

To the accomplishment of these objects, and such others as may appear hereinafter, the various features of the present invention reside in certain devices, combinations and arrangements of parts hereinafter described and then pointed out broadly and in detail in the appended claims, possessing advantages readily apparent to those skilled in the art.

The various features of the present invention will be readily understood from an inspection of the accompanying drawings illustrating the best form of the invention at present known to the inventor, in which,

Figure 1 is a view in front elevation of the tape-applying machine, the tape-severing knife and the tape-guides or presenters being shown in the position they occupy during the normal tape-applying operation;

Fig. 2 is a view in left side elevation;

Fig. 3 is a detail view, similar to Fig. 1, the plate carrying the mechanism for predetermining variably the stroke of the tape pull-off having been removed to expose the interior parts;

Fig. 4 is a detail view in front elevation of the work guide showing its position relative to the cutting block when the work-supporting roll, (shown in construction lines), is lowered to permit the insertion of the work into the machine;

Fig. 5 is a detail view in underside plan of the taped eyelet row;

Fig. 6 is a detail view, similar to Fig. 3, the tape-severing knife and the tape guides or presenters being shown in the position they occupy during the tape-severing operation;

Fig. 7 is a detail view in front elevation of the tape pull-off cam actuating ratchet and the devices which transfer the point of engagement of the pawl from the ratchet flat to the first operative tooth adjacent thereto;

Fig. 8 is a detail sectional elevation, the tape-applying hammer, the tape-severing knife and the tape guides or presenters having the same positions as that of Fig. 6;

Fig. 13 is a detail view in sectional plan on the line 13—13, Fig. 8.

Generally, the illustrated embodiment of the present invention is provided with a tape-applying mechanism, a work supporting roll, a device for pulling off tape from the main tape source of supply and for forming a slack tape source of supply from which the tape-applying mechanism withdraws tape free from the main source of supply tension as needed, a tape-severing knife which in ordinary tape-applying operations may merely sever the tape to produce a predetermined length but which in eyelet row taping operations severs the tape to produce a predetermined length and shapes the leading and trailing edges of the tape to fit the bent runs at one or both ends of the eyelet rows, which tape-severing knife in all taping operations is thrown automatically both in and out of operation, and two tape-engaging devices which in the normal tape-applying operation act as tape guides in cooperation with the tape-severing knife cutting block and which, after the tape is severed, are operated in two directions normal to each other to permit one of them to act as a tape-presenter to feed the leading edge of the tape from the point of cut-off into the zone of activity of the tape-applying mechanism.

Referring now to Fig. 5 the pliable material to which the reinforcing strip is to be applied is shown as a shoe upper part 14 provided with a folded margin 15. That portion of the flesh face of the shoe upper part 14, which is the face exposed to view in Fig. 5 and through which a row of holes is to be formed to receive buttons, hooks or eyelets, is called herein the eyelet row. As shown in Fig. 5, the eyelet row is covered by a piece of tape 16 placed alongside but without the plies of the folded margin. The folded margin 15 has a straight run 17 along one side of the eyelet row, a bent run 18 along one end of the eyelet row, and a bent run 19 along the other end of the eyelet row. The tape 16 is applied to the eyelet row with one longitudinal edge 20, engaged with the straight run 17, and with shaped ends 21 and 22, engaged, respectively, with the bent runs 18 and 19.

The applying of the tape 16 to the eyelet row is accomplished by the combined action of the roll work support 23 (Figs. 1, 2 and 3) and a pressing member or hammer 24. The pressing member 24 is detachably connected to the bottom of a head member 25, or lever, which has a vertical movement and also a rocking movement laterally. The oscillating head 25 is mounted on the main frame 26 of the machine and it receives its oscillating movement from an eccentric 27, (Fig. 8), on a driving shaft 28 carried by the main frame. The head 25 is provided with a slot 29, (Figs. 1, 3 and 8), through which extends a stud 30 fast on the main frame 26, said stud having a block 31, (Figs. 1 and 8), which is mounted in the slot 29 and is journaled on the stud 30.

As the shaft 28 is rotated the eccentric 27 thereon gives the head 25 an up and down movement and also a rocking movement laterally, said movements causing the face of the pressing member 24 to move toward and from the work 70 on the work support and also to have a lateral rocking contact with the work.

In the machine disclosed in the patent to Osgood, No. 1,549,376, the head, corresponding to the head 25, slides on the block in a direction radial to the eccentric pin or strap during the

rotation of the eccentric, that is, in a straight line which intersects both the axis of the shaft and the center of the stud. With this construction the right-hand corner of the hammer, viewing the left side of the machine, passes through an orbital path which differs from the path passed through by a regular four motion device, having equal up and down and equal lateral steps, in that the square corners thereof are rounded. With such a mode of operation, the right-hand corner of the hammer, in passing from the vertical to the horizontal traverses a curve in the path and thus imparts a glancing blow to the work at the moment of initial impact.

In the illustrated embodiment of the present invention, the head 25 slides on the block 31 in a direction non-radial to the eccentric during its rotation, that is, in a straight line which extends downwardly and laterally towards the toe of the hammer across the straight line intersecting the axis of the shaft 27 and the center of the stud 30. With this construction and mode of operation the hammer has a compound movement during its descent into contact with the work. That is, the hammer in moving downwardly also moves laterally towards the unsecured portion of the tape extending between the work and the tape guide 145. Stated in another way, in the former construction, the hammer impacted the work initially while moving towards the down-going side of the work-supporting roll. In the present construction, the hammer impacts the work initially while moving towards the up-going side of the work supporting roll.

The work-supporting roll 23, which is covered by a rubber jacket 32, is freely rotatable upon one end of a carrier, 33, (Fig. 2), the other end of which is provided with lateral bosses 34 and 35, (Fig. 1), each of which is provided with a conical cavity 36 which receives the conical end 40 of a screw 37 secured to the walls of a hollow frusto-conical domed shell 38, (Fig. 2), connected to the frame 26 through a vertical web 380. With this construction the carrier 33 may rock upon the conical ends of the screws 37.

The front end of the carrier 28 is provided also with conical cavities, (Fig. 1), which receive the conical ends of screws 39 carried by a yoke 40 constituting, in effect, one link of a toggle, (Fig. 2). The other link 41 of the toggle comprises a yoke which is rotatably mounted on a horizontal rod 42 carried by the base of the shell 38. The floating pivot for the toggle links 40 and 41 is formed by a pair of conical ended screws 43 carried by the link 41 and arranged to engage conical cavities formed in the lateral sides of the yoke 40.

In order to force the work-supporting roll 23 upwardly towards the tape-pressing member 24 yieldingly, the back face of the yoke 40 is provided with a pair of spaced arms 44, (Fig. 1), which support a horizontal rod 45 upon which a block 46, (Fig. 2) is pivotally mounted. The block 46 receives one end of a screw threaded rod 47 the other end of which is provided with a nut 48 threaded into the shell 38 and provided with a spring tension adjusting hand wheel 49. Coiled around the rod 47 and interposed between collars 50 and 51 thereon is a spring 52.

In order to break the toggle and thus lower the work-supporting roll 23 to facilitate the insertion and removal of the work into and out of the machine, respectively, the link 41 is provided with an arm 53, (Fig. 2), which is pivotally connected to the upper end of a treadle rod 54. The

dome of the shell 38 is provided with an adjustable bolt 55, (Fig. 2), the lower end of which is arranged to engage a vertical extension 56 on the carrier 33 and thus act as a stop to limit 5 the upward movement of the work-supporting roll under the influence of the spring 52.

This manner of supporting the carrier for the roll on the conical ends of adjustable screws is 10 advantageous as it provides for greater manufacturing tolerance, in that the roll may be brought into correct operating position readily after assembly, for ease in take-up in the case of wear, and for the formation of the toggle through which a heavy pressure is transmitted 15 from the spring to the roll.

The work is guided into the machine by the curved surface 57 (Figs. 1, 2, 4 and 11) on a thin shield 58, forming a guard for the right-hand side of the work-supporting roll, viewing 20 Figs. 1, 2 and 4. The shield 58 is formed on a block 59 (Fig. 11), which is secured to the carrier 33.

The work is guided during the operation of the machine by a guide 60 on the block 59. The 25 guide 60 is provided with an edge 61 arranged to engage the external edge of the shoe part 14 (Fig. 5) which is parallel to the straight run 17. The edge 61 is formed between two laterally projecting upper and lower flanges 62 30 and 63, respectively, the upper one being short and straight (Fig. 4), and the lower one being long and curved to extend over and conform to the upgoing side of the work-supporting roll close to the initial point of operation of the 35 tape-applying presser member 24. As shown in Fig. 4, this construction produces a passageway, for the edge of the work, which converges in the direction of the line of feed. The guide 60 is provided, adjacent the left-hand end of the 40 flange 62 (Fig. 4), with an extension 64 which extends vertically in back of the pressing member 24 and prevents work having abrupt curvatures from being improperly located in the guide.

As usual in this type of machine the tape is 45 coiled in a roll (Figs. 1 and 2), constituting the source of supply. From the source of supply the tape passes under a roll 65 (Fig. 3), which is journaled in one ear formed on a cover plate 66 secured to frame 26. The tape is pressed 50 against the top of the cover plate 66 by the head of a pawl like device 67 pivoted from another ear on the cover plate and urged to engage the tape under the mild tension of a coiled spring 68 interposed between the tail of the device 67 and the top of the cover plate. The 55 tail of the device 67 is provided with a slot 69 through which the tape passes on its way from the source of supply to the roll 65.

From the tension device 67 the tape passes 60 around a roll 70 carried by the free end of a pull-off lever 71 (Figs. 3 and 6). The other end of the pull-off lever 71 is secured to a rock shaft 72 which is journaled in a hub 73 (Fig. 2), formed on a plate 74 the head of which is secured 65 to the web 330. The rear end of the rock shaft 72 is provided with a collar 75 to which one end of a spring 76, coiled about the hub 73 and interposed between the plate 74 and the collar 75, is secured. The other end of spring 76 is hooked into the plate 74 and tends to hold the 70 roll 70 under an extremely light tension in contact with the tape.

From the roll 70 the tape passes under a roll 77 mounted on one end of the front face of a 75 U shaped lever 78 (Fig. 11), secured centrally

to a rock shaft 73 journaled in a hub 80 on the plate 74. Coiled about the hub 80 and interposed between the plate 74 and a collar 81 on the shaft 79 is a coiled spring 82 having one end secured to the plate and the other end secured to the collar. The spring 82 tends to rotate the rock shaft 79 clockwise, viewing Figs. 3 and 6, and thus hold the lever 78 engaged with a pin 83 (Fig. 6), projecting forwardly from a bracket 84 secured to the front face of the plate 10 74. Movement of the rock shaft 79 in the other direction is limited by an adjusting screw 85 carried by the lever 78, the lower end of which is arranged to engage one of the flats on an extended hexagonal nut 850, threaded on a rod 15 851 projecting forwardly from the plate 74.

From the roll 77 the tape passes over a roll 86 carried by the front face of the other end of the lever 78. From the roll 86 the tape passes about a roll 87 carried by the plate 74. From 20 the roll 87 the tape passes over an inclined surface 88 formed in the upper end of a cutting block 89 secured to the plate 74 with its cutting bed surface directed to the right, viewing Figs. 3 25 and 6.

The tape passes over the cutting bed surface of the cutting block 89, then over an inclined surface 90 formed in the lower end thereof, to the point of operation beneath the tape-applying member. The opposite sides of the cutting block 30 35 adjacent the inclined surfaces 88 and 90 form ways which hold the tape from lateral movement during its passage over the block.

The adhesive face of the tape engages the peripheral surfaces of the rolls 65, 86 and 87 (Fig. 35 3). These rolls are provided with peripheral grooves so that the adhesive face of the tape engages only the lands between the grooves. The other rolls engaged by the tape are of the usual flanged type. 40

From the construction described it is apparent that during the feed of the taped work over the work-supporting roll 23 by the pressing member 24 there is a tendency for the pressing member to pull tape from the source of supply at each 45 feeding step. But as the tacky face of the tape in the source of supply is stuck somewhat to the non-tacky face in an adjacent convolution, considerable force is required to unwind the tape. It is, therefore, undesirable to rely upon 50 the pressing member 24 to pull the tape from the source of supply as the pulling force exerted thereby would drum-head the tape between the work and the lower corner of the cutting bed 89 and thus interfere with the proper application 55 of the tape to the work.

In the illustrated embodiment of the present invention, the lever 71 is actuated in a manner presently to be described to free a predetermined amount of tape from its source of supply tension and to hold this freed tape in a loop constituting a source of supply of slack tape which is used up as needed during the tape-applying operation. In the illustrated embodiment of the present invention, the entire amount of tape required by the pressing member to tape the work is freed from the source of supply tension during a single stroke of the lever 71 which amount, however, may be varied in accordance with the requirements for different lengths of the eyelet 60 rows or the lengths of the tape needed to tape the particular piece of work operated upon. 65

To this end the lever 71 is provided with a follower roll 91 (Figs. 2, 3 and 6), which is normally held by the pull exerted by the hammer 24 on 75

the loop of tape held by the lever in the path of movement of a peripheral cam 92 secured to a shaft 93 journaled in a hub on the plate 74. The shaft 93 is provided with a ratchet 94 which is driven by the head of a pawl 95 arranged to engage the teeth on the periphery of the ratchet, one tooth at a time, and thus rotate the cam shaft 93 in a step by step manner. The pawl 95 is pivoted on a jointed lever 96, one end of which is pivoted on a pin 97 carried by the oscillating head 25 and the other end of which is pivoted on the rock shaft 72. With this construction the lever 96 is oscillated during each cycle of operations of the tape-applying hammer 24 to cause the pawl 95 to rotate the cam shaft 93. The periphery of the ratchet 94 is provided with a smooth portion 98 (Fig. 7), adjacent the first tooth 99 thereon. The head of the pawl is depressed towards the periphery of the pawl in the usual manner by a leaf spring 100, carried by the lever 96, having its free end engaged in a notch 101 formed in the tail of the pawl 95.

In order to hold the cam shaft 93 stationary while the pawl 95 rides back to engage the next tooth in the ratchet 94 the cam shaft 93 is provided with a second ratchet 102, (Fig. 2), outside the cam shaft hub, the teeth of which ratchet are engaged successively by a pivoted spring pressed pawl 103 carried from the plate 74. The teeth in the ratchet 102 extend completely about its periphery in order to hold the cam shaft 93 stationary during the time the pawl 95 vibrates on the smooth portion 98 of the ratchet 94.

In order to prevent the cam 92 and the ratchet 94 from getting out of timed relation the cam 92 carries a pin 1030 which passes through the ratchet 94 and is suitably secured in position as by a bolt, (not shown).

For convenience in disclosure, Fig. 6 may be considered as showing the position of the parts at the commencement of the pull-off cycle in which the maximum amount of tape is pulled from the source of supply. The lever 71 is illustrated in full lines as having reached its limit of movement on the stroke on which it delivers tape free of the source of supply tension for the operation of the tape-applying hammer 24. In this position of the lever 71 the follower roll 91 thereon engages the idle portion on the hub of the cam 92 and the pawl 95 is engaged with the first tooth 99 on the ratchet.

Oscillation of the lever 96 causes the pawl 95 to rotate the ratchet 94 in the direction of the arrow, Fig. 3, by engagement of the teeth thereon successively until the pawl reaches the smooth portion 98 on the ratchet on which portion the pawl vibrates idly. Owing to the rapid vibration of the lever 96 this rotation of the ratchet occurs in about a second.

During this rotation of the cam shaft 93 the cam 92 moves the pull-off lever 71 from the full line position of Fig. 6 to the construction line position thereof thus causing the pull-off to pull the maximum amount of tape from the source of supply. When during the rotation of the cam 92 its high portion passes by the follower 91 the pull-off lever 71 is freed to the influence of both the spring 76 and the hammer 24. The spring 76 holds the slack tape pulled off the source of supply in a loop. The hammer 24 in applying tape to the work eats into this loop of tape thereby overcoming the influence of the spring 76 and causing the pull-off lever 71 to move from

the construction line position of Fig. 6 back to the full line position thus completing the pull-off cycle.

With this construction the pull-off, in a single stroke in one direction, pulls off from the source 5 of supply all the tape required by the hammer 24 to tape the particular piece of work next to be operated upon. The pull-off stroke occurs between the tape-applying operations upon successive work pieces. 10

The illustrated embodiment of the present invention is designed to operate upon eyelet rows or other pieces of sheet material which vary widely in size, some requiring the application of a short length of tape, and others the application of long lengths and still others the application of a length longer than the short piece and shorter than the long piece. 15

In order that the pull-off and tape-delivery strokes of the pull-off lever 71 may be varied in accordance with the particular length of tape required by the hammer 24 to tape the work operated upon, the machine is provided with an indicating plate 104 provided with openings which, respectively, receive the end of the rod 25 85 and a similar rod 107 on the plate 74, (Fig. 3), nuts 108 (Fig. 1), being used to secure the indicating plate 104 in position. The plate 104 is provided with an arm 109, (Fig. 2), the hub of which is secured to a stub shaft 110 journaled 30 in the plate. The stub shaft 110, on the other side of the plate, is provided with a cam 112 arranged to engage a pin 113 projecting forwardly from the pull-off lever 71.

The free end of the arm 109 loosely carries a 35 pin 114, (Fig. 2), having a knurled operating head 115 and an end adapted to be inserted into any one of a plurality of holes 116, (Fig. 1), in a quadrant 117 formed on the surface of the plate 104. The pin is held in any selected one of the 40 holes by a leaf spring 118, (Figs. 1 and 2), one end of which is secured to the arm 109 and the other end of which engages a collar 119 on the pin 114, this end of the spring being yoked to embrace the pin loosely. 45

When the pin is located as shown in Fig. 1, the cam 112 has moved the lever 71 to the right so that the follower roll 91 is picked up by the cam 92 late in the rotation of the cam shaft 93. In the position indicated in Fig. 1 the shortest possible length of tape is pulled from the source of supply by the pull-off lever and delivered, free of the source of supply tension, for the operation of the tape-applying hammer 24. 50

Shifting the pin 114 to the left, (Fig. 1), into 55 one of the other holes 116 causes the cam 92 to pick up the roll 91 earlier in the rotation of the cam shaft 93 thus to impart a longer pull-off stroke to the lever 71, the lowermost hole 116 indicating the position of the cam 112 to locate the pull-off lever 71 initially to receive its longest pull-off stroke. 60

It is usual in this type of tape-applying machine to provide a tape-severing knife to sever the tape. In the illustrated embodiment of the 65 invention the tape-severing knife 119, (Figs. 9, and 10), is Y shaped in order that it may cooperate with the bed 89 and in a single cutting stroke shape the trailing edge on the piece of tape being applied to the eyelet row, (Fig. 5), to 70 fit the bent run 22, and at the same time shape the leading edge on the next piece of tape to be applied to the next succeeding eyelet row to fit the bent run 21 thereon.

As indicated in Fig. 10 the cutting edge A of 75

the tape-severing knife is shaped as in a chisel except that instead of the bevels meeting, they merge with a narrow flat forming the leading edge of the knife.

5 The tape-severing knife is formed upon a block which is secured to one end of a slide 121 mounted to slide beneath cover plates 122, (Fig. 11), in a slideway 123 formed in a bracket 124 bolted to the plate 74. It will be apparent from an inspection of Figs. 5, 9 and 10 that the Y shaped knife produces a V shaped piece of waste constituting the material lying between the branches of the Y during the tape-severing operation. The successive pieces of waste material stick to each other but the plies so formed work backwardly in the space between the branches of the Y into a groove 120 formed in the rear face of the slide 121 from which they drop harmlessly. Interposed between the cover plates 122 and secured to the slide 121 is a rack 125 which is engaged by teeth on a segment 126 having a hub 127, (Fig. 11), secured to a horizontal shaft 128 journaled in a hub 129 on the plate 74.

As pointed out hereinbefore Fig. 6 may be considered as showing the position of the parts at the commencement of the pull-off cycle. As shown in Fig. 6 the tape-severing knife 119 is positioned to sever the tape engaged with the cutting bed 89. During the pull-off cycle the tape-severing knife 119 is retracted from the cutting bed 89, power for operating the knife is stored in a spring, the knife is latched in its retracted position to hold it from movement against the power of the spring, and finally the latch is tripped to free the knife to the influence of the spring which operates to drive the knife against the tape on the cutting block to shape the trailing end of the tape being applied and the leading end of the tape next to be applied.

40 To this end an arm 130, (Figs. 3 and 6), is secured adjustably by one end to the front face of the segment 126. The arm 130 is provided with a curved slot 131 which embraces the shank of a bolt 132 projecting from the front face of the segment, there being a nut 133 to clamp the arm 130 in its desired position of adjustment. The arm 130 adjacent its upper end is provided with a roll 134, which during the rotation of the cam shaft 93 is engaged by the cam 92.

50 With this construction the segment 126 is moved from the position of Fig. 6 to that of Fig. 3 to retract the tape-severing knife from the cutting bed 89. During this movement of the segment 126, power is stored in a spring 135, (Fig. 11). One end of the spring is hooked over a pin 136, (Fig. 8), projecting rearwardly from the plate 74. The other end of the spring is secured to a collar 137 on the shaft 128, the spring being arranged in a coil on a shoulder formed on the 55 collar 137.

In order to latch the tape-severing knife in its retracted position, (Fig. 3), against the power of the spring 135, the upper end of the arm 130 is curved to ride under a trigger 138 carried by one 60 end of the lever 78 and lift it slightly against the tension of the spring 82 which causes the trigger 138 to snap into engagement with a ledge 139 formed on the end of the arm 130 at one side of the curved portion thereof.

70 In order to supplement the action of the locking ratchet 102 to positively prevent the accidental rotation of the ratchet 94 when the parts are in the position of Fig. 3, the arm 130 is provided with a vertically adjustable block 140 hav-

ing a laterally extending portion arranged to be engaged by the pin 1030.

After the tape-severing knife has been thrown out of operation the pawl 95 vibrates on the smooth portion 98 on the ratchet 94 until the 5 hammer 24 has withdrawn from the supply of slack tape held by the pull-off sufficient tape to tape the work being operated upon. The tape-severing knife and its associated parts are held in the position of Fig. 3 until the tape-applying hammer 24 eats up all the slack tape which in accordance with the initial adjustment for length the tape pull-off lever 71 is capable of delivering. As soon as the tape delivering stroke of the pull-off lever 71 is limited by the cam 112, the tape-applying hammer 24 during its taped work feeding movement subjects the run of tape extending from the taped work to the roll 70 to tension sufficient to depress the roll 86 and thus withdraw the trigger 138 from the ledge 139 thereby releasing the tape-severing knife to the influence of the power stored in the spring 135, which thereupon imparts the tape-severing stroke to the tape-severing knife. During this stroke the segment moves from the position of Fig. 3 to that 25 of Fig. 6.

In order to rotate the ratchet 94 slightly in the direction of the arrow, (Fig. 3), and thus transfer the point of operation of the pawl 95 from the smooth portion 98 to the first tooth 99 in 30 the ratchet 94 in readiness for the next pull-off cycle the arm 130 is provided with a roll 134 which, in Fig. 7 moves, when the arm is unlatched, through the three positions shown to engage the cam 92 and rotate the ratchet. 35

In order to bring the leading edge of the tape connected to the source of supply from the position it occupies while shaped by the tape-severing knife down the cutting bed 89, under the lower corner thereof and into the zone of activity of the tape-applying hammer 24, the machine is provided with two tape presenters 144 and 145 which during the normal tape-applying operations act as tape guides in cooperation with the cutting bed 89. 40

45 The tape-presenter 144 comprises a strip 146 having a bent lower end 147 arranged to press the tape against the cutting bed yieldingly so that it may ride upwardly upon the tape and so that it may feed the tape down the cutting bed when 50 moved downwardly. The upper end of the strip 146 is wider than the lower end and is mounted to slide upon a plate 148 secured to the plate 74. As shown in Fig. 13 the strip 146 slides on the plate 148 beneath cover plates 149 and 150 55 secured to the plate 148, the plates being separated to form a guideway for the strip 146 by shims 151 inserted between the plates and engaged with the lateral sides of the strip.

The strip 146 is secured to the back of a rack 60 152 the teeth on which are meshed with the teeth on the segment 126. With this construction the tape-presenter 144 is moved from the position of Fig. 6 to that of Fig. 3 to feed the leading end of the tape down the cutting bed and below the 65 lower end thereof. When the tape-severing knife is operated to sever the tape the tape-presenter is elevated from the position of Fig. 3 to that of Fig. 6.

70 When the tape-presenter 144 is in the position 70 of Fig. 6 and for the major portion of its downward tape-presenting stroke it grips the tape so as to resist the tendency of the tape-pull-off device to pull the tape upwardly from beneath the tape-presenter. Just prior to the movement of 75

the tape-presenter 144 into the position of Fig. 3 the freshly made leading edge of the tape has been engaged by the tape-applying hammer so that it is no longer necessary for the tape-presenter 144 to grip the tape tightly against the cutting block 89.

To relieve the pressure of the tape-presenter 144 on the tape as the tape-presenter moves into the position of Fig. 3 the cutting block is reduced 10 slightly in thickness in that locality sufficient to permit the tape, during the tape-applying operation, to slip readily beneath the tape presenter which then acts as a tape-guide.

The tape-presenter 145 is first retracted away 15 from the cutting bed to allow the presenter 144 to feed the leading end of the tape down the cutting bed and to dangle below the lower corner thereof, and then is returned to the position of Fig. 3 to press the tape into engagement with the 20 inclined surface in the lower corner of the cutting bed.

The tape-presenter 145 comprises a main blade 153 and an auxiliary blade 154 secured together, back to back, by a screw 155. The upper blade 25 153 is provided with two slots 156 and 157 which embrace the shanks of two screws 158 and 159 projecting downwardly from the bottom of the bracket 123 beneath the guideway 121. The lower blade 154 is provided with a slot 160 which 30 embraces the shank of the screw 158. The heads on the screws 158 and 159 overlap the blades 154 and 153, respectively, the construction being such as to permit the blades to slide longitudinally in engagement with the shanks and heads 35 of the bolts 158 and 159.

The leading end of the blade 154 is wide enough to extend across the cutting bed but is provided with a narrower tongue which is shaped to engage the downwardly extending inclined 40 surface on the lower end of the cutting bed. The tape-engaging end of the blade 153 is narrower than the leading end of the blade 154 and is shaped to press the tape into engagement with the inclined surface on the lower end of the 45 cutting bed.

In order to retract the tape-presenter 145 from the cutting bed 89, the slide 121 carries a cross pin 161 upon which a latch 162 is pivoted. The latch 162 is provided with a lug 163, which 50 when the tape-presenter is in the position of Fig. 8 is depressed into a slot 164 formed in the blade 153, by a leaf spring 165 one end of which is secured to the rack 125 and the other end of which engages the latch 162. With this construction when the tape-severing knife is being 55 retracted the lug 163 engages the blade 153 and carries the tape-presenter 145 along with the slide 121. To trip the lug 163 to enable the tape-presenter 145 to return to engage the tape prior 60 to the tripping of the tape-severing knife, the latch 162 is provided with an inclined surface 166, arranged to engage a cross-pin 167 projecting rearwardly from a knife guard plate 168 adjustably secured to the front face of the guideway 123. The tape-presenter 145 is returned 65 into engagement with the tape on the cutting bed 89 by a coiled spring 169 one end of which is secured to a screw 159 and the other end of which is secured to a pin 170 depending from the blade 153. When the tape-severing knife is 70 operated to sever the tape the lug 163 is reinserted into the slot 164 by the leaf spring 165.

Nothing herein explained is to be interpreted as limiting the various features of the present 75 invention in the scope of its application to use

in connection with the particular machine or the particular mode of operation or any combination thereof selected for purposes of illustration and explanation. While the particulars of construction herein set forth are well suited to one mechanical form of the invention and to the uses to which it is put, it is not limited as to these uses, nor to these details of construction, nor to the conjoint use of all its features, nor is it to be understood that these particulars are 10 essential since they may be modified within the skill of the artisan without departing from the true scope of the actual invention, characterizing features of which are set forth in the following claims by the intentional use of generic 15 terms and expressions inclusive of various modifications.

What is claimed as new, is:

1. A tape-applying machine having, in combination, tape-applying mechanism, tape-severing mechanism, and means independent of the operative for throwing the tape-severing mechanism automatically out of operation.

2. A tape-applying machine having, in combination, tape-applying mechanism, tape-severing mechanism, and means for throwing the tape-severing mechanism automatically into and out of operation.

3. A tape-applying machine having, in combination, tape-applying mechanism, tape-severing mechanism, means for throwing the tape-severing mechanism automatically out of operation, and mechanism rendered active in throwing the severing mechanism out of operation for automatically throwing the severing mechanism 35 into operation.

4. A tape-applying machine having, in combination, tape-applying mechanism, tape-severing mechanism, means for throwing the tape-severing mechanism automatically out of operation 40 and for retaining it out of operation, and mechanism rendered active in throwing the severing mechanism out of operation for automatically throwing the severing mechanism into operation.

5. A tape-applying machine having, in combination, tape-applying mechanism, tape-severing mechanism, and means for throwing the tape-severing mechanism automatically out of operation, latching means for retaining the tape-severing mechanism out of operation, and mechanism for automatically disengaging the latching means.

6. A tape-applying machine having, in combination, a pull-off device, means for applying a length of tape to the work and for moving the pull-off device in one direction, and means for moving the pull-off device in the opposite direction to cause it to pull tape from the source of supply.

7. A tape-applying machine having, in combination, a pull-off device, means for applying a length of tape to the work and for moving the pull-off device in one direction, means for limiting the movement of the pull-off device under the influence of the tape-applying means, and means for moving the pull-off device in the opposite direction to cause it to pull tape from the source of supply.

8. A tape-applying machine having, in combination, a pull-off device, means for applying a length of tape to the work and for moving the pull-off device in one direction, means for moving the pull-off device in the opposite direction 75

to cause it to pull tape from the source of supply, and means for varying the extent of movement of the pull-off device in at least one direction.

9. A tape-applying machine having, in combination, a pull-off device, means for applying a length of tape to the work and for moving the pull-off device in one direction, means for moving the pull-off device in the opposite direction to cause it to pull tape from the source of supply, and means for varying the extent of movement of the pull-off device in both directions.

10. A tape-applying machine, having in combination, a pull-off device, means for applying a length of tape to the work and for moving the pull-off device in one direction, and mechanism including a cam for moving the pull-off device in the opposite direction to cause it to pull tape from the source of supply.

11. A tape-applying machine having, in combination, a means for applying progressively a predetermined length of tape to the work, a pull-off device, and mechanism for moving the device progressively to cause it to pull from the source of supply a length of tape commensurate with the predetermined length of tape.

12. A tape-applying machine having, in combination, means for applying progressively a predetermined length of tape to the work, a pull-off device movable progressively in one direction under the influence of the tape-applying means, and mechanism for moving the device progressively in the opposite direction to cause the device to pull from the source of supply a length of tape commensurate with the predetermined length of tape.

13. A tape-applying machine having, in combination, means for applying progressively a predetermined length of tape to the work, a pull-off device constructed and arranged to form a loop in the tape extending from the tape-applying means to the source of supply and movable progressively in one direction under the influence of the tape-applying means to reduce the amount of tape in the loop by the extent of the predetermined length of tape, and mechanism for moving the device progressively in the opposite direction to cause it to pull tape from the source of supply to restore the amount of tape in the loop.

14. A tape-applying machine having, in combination, means for applying progressively a predetermined length of tape to the work, a pull-off device comprising a roll arranged to engage the tape in the portion thereof extending from the tape-applying means to the source of supply and a lever upon which the roll is mounted, means for holding the roll engaged with the tape under a light tension sufficient to cause the roll to form a loop in the tape and permit the lever to move progressively in one direction under the influence of the tape-applying means to withdraw from the loop a length of tape commensurate with the predetermined length of tape, and a cam for moving the lever progressively in the opposite direction to cause the roll to pull tape from the source of supply to restore the amount of tape in the loop.

15. A tape-applying machine having, in combination, means for applying progressively a predetermined length of tape to the work, a pull-off device comprising a roll arranged to engage the tape in the portion thereof extending from the tape-applying means to the source of supply and a lever upon which the roll is mounted, means for holding the roll engaged with the tape under a light tension sufficient to cause the roll to form

a loop in the tape and permit the lever to move progressively in one direction under the influence of the tape-applying means to withdraw from the loop a length of tape commensurate with the predetermined length of tape, a cam for moving the lever progressively in the opposite direction to cause the roll to pull tape from the source of supply to restore the amount of tape in the loop, and an adjustable stop for variably limiting the movement of the lever in one direction.

16. A tape-applying machine having, in combination, means for applying progressively a predetermined length of tape to the work, a pull-off device, and means for operating the device, before the tape is applied to the work, progressively in one direction to pull a length of tape from the source of supply commensurate with the predetermined length of tape.

17. A tape-applying mechanism having, in combination, a tape-applying mechanism operating in repeated cycles to apply a predetermined length of tape to the work and a pull-off mechanism operating in a single cycle before the operation of the tape-applying mechanism to pull a length of tape from the source of supply commensurate with the predetermined length.

18. A tape-applying machine having, in combination, a tape-pulling device having a single stroke in which it pulls tape from the source of supply and forms a source of slack tape supply freed from the source of supply tension, and means for applying a predetermined length of slack tape to the work.

19. A tape-applying machine having, in combination, means for pulling tape from the source of supply and holding the pulled-off tape in a source of slack tape supply and means operating after the tape has been pulled off and while the pulled-off tape is held in a source of slack tape supply for applying a predetermined length of slack tape to the work.

20. A tape-applying machine having, in combination, a tape pull-off, a tape-severing knife, mechanism for throwing the knife out of operation, and a common cam for operating the pull-off to pull tape from the source of supply and the mechanism for throwing the knife out of operation.

21. A tape-applying machine having, in combination, a tape pull-off, a tape-severing knife, mechanism for throwing the knife out of operation, a common cam for operating the pull-off to pull tape from the source of supply and the mechanism for throwing the knife out of operation successively.

22. A tape-applying machine having, in combination, a tape pull-off, a tape-severing knife, mechanism for throwing the knife out of operation, a common cam for operating the pull-off to pull tape from the source of supply and the mechanism for throwing the knife out of operation successively, and mechanism for operating the cam including a mutilated ratchet secured to the cam, a pawl, means for supporting and operating the pawl to cause it to engage the teeth of the ratchet, one at a time, successively, and to thereafter transfer the pawl to the mutilated portion of the ratchet, means for locking the ratchet from accidental movement in either direction while the pawl is engaged with the mutilated portion of the ratchet, and means for unlocking the ratchet and reengaging the pawl with the teeth on the ratchet to restart the cycle.

23. A tape-applying machine having, in com-

- bination, a tape applier, a tape pull-off, a tape-severing knife, mechanism for throwing the knife out of operation including latching means, a common cam for operating the pull-off to pull 5 tape from the source of supply and the mechanism for throwing the knife out of operation, mechanism for operating the cam including a vibratory lever, and a common mechanism for vibrating the lever and for operating the tape 10 applier to apply tape to the work and to disengage the latching means.
24. A tape-applying machine having, in combination, a work-support, a tape-applying device, a tape-guide, and means for imparting to the 15 device compound vertical and lateral movement towards the tape-guide into engagement with the work.
25. A tape-applying machine having, in combination, a tape-applying mechanism, means for 20 conducting the tape to the tape-applying mechanism including a cutting block having a flat cutting bed surface, and a knife having a cutting edge which butts against said surface for severing the tape.
26. A tape-applying machine having, in combination, tape-applying mechanism, means for conducting the tape to the tape-applying mechanism including a cutting block over which the non-tacky face of the tape is drawn and a knife having 30 a Y shaped cutting edge acting on the tacky face of the tape and in cooperation with the block for severing the tape, there being an opening leading into the knife between the branches of the Y out of which the waste pieces cut out of 35 the tape may pass in a stack.
27. A tape-applying machine having, in combination, tape-applying mechanism, means for conducting the tape to the tape-applying mechanism including a cutting block, and a knife, having 40 a straight cutting edge and two cutting edges which are curved in opposite directions, respectively, and which branch from the straight cutting edge, cooperating with the block for severing the tape and for simultaneously shaping the trailing 45 edge on the length of tape being applied by the tape-applying mechanism and the leading edge on the length of tape next to be applied to fit runs on eyelet rows bent in opposite directions.
28. A reenforcing machine having, in combination, a support for a piece of sheet material having an eyelet row and a folded margin extending in a straight run along one longitudinal edge of the eyelet row and in at least one bent run 55 around the ends, respectively, of the eyelet row, a single knife for shaping the leading and trailing edges of a stay to fit, respectively, the ends of the eyelet row, and means for applying the stay to the eyelet row with one of the longitudinal edges of 60 the stay and its opposite ends engaged, respectively, with the straight and bent runs.
29. A reenforcing machine having, in combination, a support for a piece of sheet material having an eyelet row and a folded margin extending 65 in a straight run along one longitudinal edge of the eyelet row and in runs bent in opposite directions, around the ends, respectively, of the eyelet row, and a single knife for shaping the leading and trailing edges of a stay to fit, respectively, the ends of the eyelet row, and means for applying the stay to the eyelet row with one end of the longitudinal edges of the stay and its opposite 70 ends engaged respectively, with the straight and bent runs.
30. A reenforcing machine having, in combination, a support for a piece of sheet material having an eyelet row and a folded margin extending in a straight run along one longitudinal edge of the eyelet row and in a bent run around at least one end of the eyelet row, a single knife for producing a stay having end edges and having one longitudinal edge shorter than the other, and means for applying the stay to the eyelet row with the shorter longitudinal edge of the stay and one end edge thereof adjacent, respectively, the straight run and a bent run. 5
31. A tape-applying machine having, in combination, tape-applying mechanism, means for conducting the tape to the tape-applying mechanism including a cutting block over which the non-tacky face of the tape is drawn, a tape-guide for guiding the tape as it is drawn over the cutting block, a tape-severing device in the path of operation of which the tape-guide normally lies, 15 interposable between the tape-guide and the work, and mechanism automatically thrown into operation upon the drawing of a predetermined length of tape through the tape-guide for withdrawing it from the path of operation of the tape-severing device and for actuating the device to sever the tape. 20
32. A tape-applying machine having, in combination, tape-applying mechanism, means for conducting the tape to the tape-applying mechanism including a cutting block over which the non-tacky face of the tape is drawn, a combined tape-presenter and tape-guide acting upon the tape as it is drawn over the cutting block, a tape-severing device, in the path of operation of which the combined tape-presenter and tape-guide normally lies, mechanism for withdrawing the combined tape-presenter and tape-guide from the path of operation of the tape-severing device and for actuating the device to sever the tape, and 30 mechanism for throwing the tape-severing device out of operation and for returning the combined tape-presenter and tape-guide into the path of operation of the device and feeding the leading edge of the tape over the cutting block towards 35 the work. 40
33. A tape-applying machine having, in combination, tape-applying mechanism, means for conducting the tape to the tape-applying mechanism including a block over which the non-tacky face of the tape is drawn, two tape guides for guiding the tape as it is drawn over the block, and means for relatively operating the guides in two directions normal to each other. 50
34. A tape-applying machine having, in combination, a work support, a tape-applying device, a tape guide, and means for imparting to the device a compound vertical and lateral movement towards the tape guide into engagement with the work comprising an eccentric, a fixed pivot, a block pivoted thereon and a head for the device having a strap connection with the eccentric and a slot, in which the block is mounted, said block and slot constraining the hammer to move into and out of engagement with the work in directions non-radial to the eccentric. 55
35. A tape-applying machine having, in combination, a roll work support, a tape-applying device and means for imparting four motions to the device including a compound vertical and lateral movement towards the up-going side of the roll into engagement with the work. 70
